CAN OPENER

Edward C. Eberts, Indianapolis, Ind., assignor to
Stokely Brothers & Company, Inc., Indianapolis, Ind., a corporation of Indiana

Application June 21, 1939, Serial No. 280,241

1 Claim. (CL 30—16)

This invention relates to improvements in can openers, and more particularly to a metal can-puncturing device having associated therewith a shield or guard element for reducing and deflecting the initial spurt of the liquid contents from the metal container when punctured.

Metal containers are extensively used in the packaging of beer, ale, fruit and vegetable products and numerous other liquid or semi-liquid materials which contain expansive gases or which develop such gases due to chemical changes in the contents after packaging. Pressure conditions are thus set up so that when the container is punctured, the compressed gases in the container cause a spurt or spray of the liquid contents through the punctured opening, which are projected at considerable distances and in unpredictable directions. The disagreeable consequences resulting from puncturing pressure-packed metal containers by means of can openers now in general use are well known.

An object of this invention is to provide a can opening device having associated with the can-puncturing portion thereof a shield or guard element so designed and constructed as to reduce and deflect the initial spurt of liquid contents from the metal container when punctured.

Another object of this invention is to provide an improved can opening device having a flexible spurt-deflecting guard associated therewith, which is inexpensive to construct and assemble, and which assumes the proper spurt-deflecting position when the can-puncturing element is placed in puncturing position.

Other objects of this invention will become apparent as the disclosure proceeds.

Various other features and advantages of the invention will be apparent from the following particular description and from an inspection of the accompanying drawing.

Although the novel features which are believed to be characteristic of this invention will be particularly pointed out in the claim appended hereto, the invention itself, as to its objects and advantages, and the manner in which it may be carried out, may be better understood by referring to the following description taken in connection with the accompanying drawing forming a part thereof, in which:

Fig. 1 is a perspective view of my improved can opener as it appears when applied to a metal container, this view showing particularly the spurt shield associated with the can-puncturing portion thereof;

Fig. 2 is a top plan view of my improved can opener as applied to a metal container;

Fig. 3 is a cross-sectional view of my improved can opener applied to a metal container, this view showing particularly the arrangement of the can-puncturing portion and spurt shield when in operative position ready to puncture the can;

Fig. 4 is a cross-sectional view of my improved can opener showing the arrangement of the can-puncturing portion and the spurt shield as they appear following the can-puncturing operation; and

Fig. 5 is a cross-sectional view of my improved can opener, showing the spurt shield provided with downwardly extending spurt-deflecting flanges.

Similar reference characters refer to similar parts throughout the several views of the drawing and the specification.

My improved can opener is particularly designed for puncturing the metal side wall or top wall of a metal container, the can opener having associated therewith a spurt guard or shield which is so arranged with respect to the can-puncturing portion so as to prevent any substantial spattering or spouting of the contents when the container is punctured. Referring more particularly to the drawing, a metal container of the usual form is illustrated, having a metal side wall 1 and a metal cover 2 connected by a rim formed by crimping the free edges of the side wall 1 and cover 2 together. More particularly, the rim may be formed by turning the edge 3 of the cover 2 downwardly as at 3 and upwardly as at 5 so as to crimp the same around the downturned edge 4 of the side wall 1 so as to form a liquid and gas-tight seal. The contents of the container which is under pressure has been designated by the letter C.

My improved spurt shield may be associated with various different types of can-puncturing devices. There is illustrated in the drawing one common type of can-puncturing device with which my improved spurt guard may be associated. The can-puncturing device shown in the figures of the drawing is generally made of steel, comprising a handle portion 11, a neck portion 12, and a can-puncturing portion 13 having a puncturing point 14.

It will be noted by referring more particularly to Figs. 1 and 2, that the can-puncturing portion 13 is provided with tapered cutting edges 15 which taper down to the point 14. Thus, when the can is punctured, a triangular-shaped

opening is formed therein. The can opener is provided with a rim gripper element which provides a fulcrum about which the handle portion 11 and the can-puncturing portion 13 may be swung. The gripper element may comprise a prong 16 which is struck out from the body of the handle portion 11 as at 17. The prong 16 is bent downwardly and has the end portion 18 thereof so shaped as to conveniently grip the rim of the metal container, as shown more particularly in Figs. 3 and 4. The handle portion 11 may be of any desired length and so shaped and formed as to provide a convenient and comfortable hand grip therefor. The neck portion 12 of the can opener is so shaped as to conveniently vault the rim of the container so as to bring the puncturing portion 13 down to the proper operative position.

It will now be appreciated that when the handle portion 11 of the can opener is swung inwardly, the puncturing portion 13 will pivot about the can rim. The point 14 of the puncturing portion bites into the metal of the cover 2 and upon upward pull of the handle portion 11 the can cover 2 is punctured, causing a sudden release of the compressed gases in the container, and causing the contents to spurt in unpredictable upward directions and spraying the surroundings and often the operator with the liquid contents.

My improved spurt shield is so designed as to effectively prevent the spouting of the liquid contents in uncontrolled directions, to break the force of the pressure-ejected liquid, to direct a substantial portion of the ejected liquid back into the container, and to diffuse that portion of the liquid which overflows along the surface of the cover and thus confine the overflow within the cover rim. The shield 20 is preferably formed of flexible resilient metal of springlike quality. The spurt shield 20 is provided with a stem portion 21 at one end thereof, which is fixedly secured to the handle portion 11 of the puncturing instrument as by rivets 22 or other securing means. The stem portion 21 merges into a shield portion 23, which is preferably substantially larger in area than the puncturing portion 13, the stem portion 21 being defined therefrom by outwardly flared hip portions 24. The shield portion 23 may be provided with side edges 25 which taper from hip portions 24 down to a blunt point 26, the point 26 extending a distance beyond the point 14 of the puncturing portion 13. The shield portion 23 at the junction of the stem portion 21 is provided with a ridge portion 27 which conforms generally to the oversprung neck portion 12 of the puncturing instrument.

By referring more particularly to Fig. 3, it will be noted that when the puncturing instrument is applied to the container and placed in position for puncturing, point 26 of the spurt shield will rest upon the top cover 2 of the container a distance beyond the puncturing point 14. Since the spurt shield is fixed to the stem portion 11 of the instrument at one end only, and since the shield is constructed of flexible metal or similar resilient material, the shield will readily flex about the rivets 22. When the handle portion 11 is pulled upwardly, as shown in Fig. 4, the point 14 breaks through the cover 2 and swings section 2a of the cover downwardly into the container. During the puncturing operation the point 26 of the spurt shield remains

pressed against cover 2, with the shield portion 23 overhanging the triangular-shaped opening formed in the cover a substantial distance, so as to provide in effect a spurt-receiving housing.

Thus, as shown in Fig. 4, the liquid-carrying gases C' will spurt upwardly and strike the inside face of the shield portion 23, immediately arresting the spouting force, return a substantial portion of the ejected liquid into the container through the punctured opening, and finally deflect the overflow downwardly where it will remain upon the depressed cover 2. It will be appreciated that the side edges 25 of the shield portion 23 may be turned downwardly to effect positive downward deflection of the ejected liquid, as shown in Fig. 5. The shield portion 23 may be given any desired area or contour. Also, if desired, the side edges 25 of the shield portion 23 may be provided with flanges so shaped as to substantially contact the top surface of the cover 2 when the instrument has been applied in operative position, thus providing a substantially enclosed housing, substantially completely covering the area of the cover which is to be punctured through.

Where it is desirable to permit prompt and full release of the compressed gases, however, it may be found desirable to leave the side edges of the shield portion open so as to effect lateral deflection of the escaping gases.

It will be apparent that my improved spurt shield may be applied to a number of different forms of can-puncturing instruments positioned to overlie the can-puncturing element so as to effectively break the force of the spouting liquid, return a substantial portion thereof to the interior of the container, deflect the overflow laterally, and confine the overflow to the depressed surface of the can cover. The spurt shield may be inexpensively constructed of suitable metal having a resilient springlike characteristic. This spurt shield may be applied as an integral part of the can opener without substantially increasing the cost thereof.

While certain novel features of the invention have been disclosed and are pointed out in the annexed claim, it will be understood that various omissions, substitutions and changes may be made by those skilled in the art without departing from the spirit of the invention.

What is claimed is:

In combination with a can opener having a can-puncturing portion, a portion adapted to grip the can edge, and a handle portion, of a metal shield element flexible substantially throughout its length including, a stem portion fixedly secured to said handle portion adjacent the can-puncturing portion and a spearhead shaped shield portion extending from said handle portion overlying said can-puncturing portion and having an area greater than said can-puncturing portion so as to overlie and overlap the opening in the can formed by said can-puncturing portion, said spearhead shaped shield portion, when not flexed, having its longitudinal cross-section shaped to generally conform to the adjacent longitudinal cross-section of said can puncturing portion and tapering to a blunt point extending beyond the puncturing point of said can-puncturing portion whereby said blunt point is adapted to rest against the wall of the container to be punctured beyond the puncturing area thereof.
